UNITED STATES PATENT OFFICE.

ORANGE O. OZIAS, OF DAYTON, OHIO.

DESIGN FOR A SCALE-BASE.

SPECIFICATION forming part of Design No. 35,941, dated June 10, 1902.

Application filed July 6, 1900. Serial No. 22,765. Term of patent 14 years.

To all whom it may concern:

Be it known that I, ORANGE O. OZIAS, a citizen of the United States of America, residing and having my post-office address in Dayton, in the county of Montgomery and State of Ohio, have invented and produced a certain new and original Design for a Scale-Base; and I hereby declare that the following is a clear, full, and exact description thereof, reference being had to the accompanying drawings, in which like numerals refer to like parts.

Figure 1 of the drawings is a top plan view of a scale-base embodying my invention and design, and Fig. 2 is a sectional view thereof on line X X of Fig. 1.

The leading or material feature of my invention and design consists of a curved hollow scale-base having a curved opening in its top, a hollow projection from one side thereof, said projection having square outer corners with an intermediate outwardly-curved central portion, said square corners being joined to said curved base by inwardly-curved inter-

mediate portions, the walls of said base being curved inward and upward, as shown. 25

In said drawings, 10 represents said curved hollow scale-base; 11, said curved opening through its top; 12, said hollow projection from one side thereof and having the square outer corners; 14, said outwardly-curved portion extending between said square outer corners of projection 12, and 15 represents said inwardly-curved portions intermediate said square corners and said curved base 10. The exterior surfaces are highly polished, which 35 the varying contour and configuration of my design blends into a pleasing effect.

What I claim is—

The design for a scale-base, substantially as shown and described. 40

In witness whereof I have hereunto set my hand this 28th day of May, 1900.

ORANGE O. OZIAS.
